UNITED STATES PATENT OFFICE.

JOHN H. GIRARD, OF LOWELL, MASSACHUSETTS.

THREADER FOR SEWING MACHINES.

1,072,601.

Specification of Letters Patent.

Patented Sept. 9, 1913.

Application filed April 24, 1913. Serial No. 763,337.

To all whom it may concern:

Be it known that I, JOHN H. GIRARD, a citizen of Canada, residing at Lowell, in the county of Middlesex and State of Massachusetts, have invented certain new and useful Improvements in Threaders for Sewing-Machines, of which the following is a specification.

My invention relates to needle threaders 10 for sewing machines. It is a device by which a sewing machine needle may be easily threaded.

In the drawings, Figure 1 is a side elevation of part of a sewing machine head and 15 Fig. 2 is a front elevation thereof.

A represents the head of a sewing machine, B represents the presser bar and M represents the presser foot.

C is the reciprocating needle carrier and 20 D is the needle. The needle D has the usual eye near the point thereof.

On the side of head A near the bottom thereof, I attach an adjustable carrier plate F by means of attaching screws 20 and 21. 25 These screws pass respectively through slots 22 and 23 in plate F which are cut on their outer sides in curves the center of each of which is in the center of the opposite slot. Thereby they permit a sort of limited rotary 30 action of plate F. Screws 20 and 21 enter suitable holes tapped in head A and threaded to receive them. Screw 20 should be long enough to permit spring 11 to be bent around it as shown. Plate F also carries 35 a stud 24 and a pin 13 for a purpose to be described.

To the bottom portion of plate F by means of a rivet 30, I pivot a swinging arm G of such shape that when it is swung down, its 40 bottom end 31 will adjoin the eye of needle D. At this end and at a point where its center will be in a position almost touching needle D and opposite the eye therein, is a tunnel or conical thread guide H 45 through which the thread K can be pushed. When guide H is in the proper position, as the thread K leaves its small end, it will pass through the eye of the needle D. This conical thread guide H has a longitudinal 50 slot 10 so cut that, when the swinging arm G is down and the conical thread guide adjoins the needle eye, it extends vertically in the direction of the length of the needle. At the other end of arm G is a tail 12 so 55 shaped that it will strike and be stopped by pin 13 on plate F when the arm G is swung

down so that conical guide H is in threading position with reference to the needle eye.

A bent spring 11 is hooked around stud 24 and passes around attaching screw 20 60 thence backward into engagement with tail 12 which is so shaped that when the arm G is swung to its lower position, spring 11 together with pin 13 will tend to hold it firmly in place. When arm G is swung 65 up after the needle is threaded, tail 12 passes the dead center and spring 11 so bears on it as to keep the arm up in position. After the needle is threaded and it is desired to raise arm G out of the way, it is lifted 70 against the pressure of spring 11 to the position shown by the dotted lines in Fig. 1 where it will not interfere with the work. It remains in the upper position until it is desired to again thread the needle. 75

The advantages of my device are the fact that it can be readily attached to a sewing machine head of any make by merely tapping and threading two holes in head A for screws 20 and 21, and it can be readily 80 adjusted in position through the medium of slots 22 and 23. It can be fixed in position by tightening screws 20 and 21. By making slot 10 in such a position that in the threading position, it is vertical and parallel with the needle eye, if the thread does not go exactly in the center of the tunnel H but gets into slot 10, it will still pass through the needle eye. Besides this, as soon as the needle is threaded and the slack of the 85 thread is being taken up, it slips up through slot 10 clear of the thread guide. My device is simple and compact and lies close 90 against the bottom and side of the head A, when not in use for threading so that it 95 does not interfere with the work.

In threading, it is best to raise the needle bar B to its highest point and to have the arm G so adjusted that at such point the conical thread guide will be in the correct 100 position. In attaching the device I find it convenient to use a small needle which I pass through the conical thread guide and the eye of needle D thus serving as a sort of pivot. The arm G in relation to 105 plate F is swung to the threading position where the tail 12 strikes pin 13 and then the whole device is swung upward on the small needle pivot abreast of the head. It is now very easy to mark on the head the 110 center of the holes for screws 20 and 21. These holes are tapped and threaded and

the device, put in place after which any slight adjustments can be made by loosening the screws 20 and 21 and shifting plate F which is permitted a limited movement by slots 22 and 23.

What I claim as my invention and desire to cover by Letters Patent, is:

In a needle threader for sewing machines, the combination with a needle, a needle carrier, and a head, of a carrier plate having two slots together with a stud and a pin, two attaching screws which pass through the slots into the head, a swinging arm which is pivoted to the carrier plate and has at one end a tail adapted to strike

the pin thereon, and a conical thread guide carried at the other end of the swinging arm in operative relation with the needle eye and having a longitudinal slot which is vertical when the guide is in the threading position, 20 together with a spring hooked around the stud and bent around one of the adjusting screws which support the carrier plate and in engagement with the tail, as described.

In testimony whereof I hereto affix my 25 signature in presence of two witnesses.

JOHN H. GIRARD.
